UNITED STATES PATENT OFFICE

CHARLES A. FRENCH, OF RIVERSIDE, ILLINOIS

SEMIFLASH BOILER

Application filed February 21, 1930. Serial No. 430,199.

This invention relates to a steam generating system. More particularly it relates to means for firing up a system of the semi-flash type.

The main object of the invention is to 5 provide means for rapidly firing up a semi-flash boiler having a storage drum.

Another object is to provide means for automatically removing a major portion of the water from the storage drum when the 10 system is out of operation.

These objects and others, which will be apparent, are accomplished by the arrangement and functioning of elements as shown in the drawing and described in the detailed 15 description to follow.

The drawing shows diagrammatically a condensing steam power plant. A preheating coil 1, a vaporizing coil 2, and a super-heater coil 3 are arranged within heat 20 resisting walls 4 and comprise the boiler of the system. A burner 5 is positioned and adapted to be operated to supply heat to the boiler.

A feed water pump 6 communicates with a hot well 7 by means of a pipe 8 with one 25 end of the preheating coil 1, by means of a pipe 9. The other end of the preheating coil communicates with one end of the vaporizing coil 2. A water forcing means shown as a pump 10 is arranged with its discharge 30 side connected to the same end of the vaporizing coil 2. The other end of the vaporizing coil 2 is connected with the top of a circular storage drum 11 at a tangent thereto.

A cylindrical partition 12 spaced from the 35 side walls of the drum 11 and an annular bottom member 13 joining the partition to the walls of the drum divide the drum into two chambers communicating at the top. The outer chamber 14 is annular in cross section 40 and has a small capacity compared to the inner chamber 15. An outlet pipe 16 communicates with the bottom of the inner chamber 15 and with a pipe 17 leading to the intake of the pump 10. A similar outlet pipe 45 18 communicates with the bottom of the chamber 14 and with the pipe 17 leading to the pump. The outlet pipe 18 is at a higher level than the outlet pipe 16. Each of the 50 outlet pipes 16 and 18 are provided with check valves 19 which allow water to flow

from the respective compartments and prevents the return flow thereto.

A steam outlet pipe 20 communicates with the top of the drum 11 and with one end of the super-heating coil 3. The other end of the super-heating coil leads to a steam communicating means, such as the engine 21 shown in the drawing. Exhaust steam from the engine is conducted to a condenser 22. Condensate from the condenser is delivered to 60 the hot well 7.

As the system shown is of the closed circuit condensing type, the water is continually circulated through the cycle. Means may be provided for adding additional water to 65 supply the small amount lost, such as shown in applicant's U. S. Patent No. 1,617,586. There is never enough water in a system of this kind to fill the storage drum complete. If the water in the hot well becomes depleted 70 due to an excess capacity of the feed water pump for the steam being consumed and condensed, means may be provided such as shown in applicant's U. S. Patent No. 1,703,228, for preventing the pump from becoming air bound. As this invention is not concerned with the water supply to the system and as such means are old in the art and are not necessary for the functioning of a device embodying the present invention, 75 they have not been illustrated or described.

A drain pipe 23 is connected to the bottom of the drum 11 and to a small chamber 24, which contains a thermo-syphon. The chamber 24 is positioned in heat exchanging relation with the hot products of combustion from the burner 5. The siphon element 25 is provided with a valve extension 26, which is adapted to close the pipe 23 when the element is heated. A pipe 27 connects the 80 chamber 24 to the hot well 7.

In the normal operation of the power plant shown in the diagram, the burner 5, the feed water pump 6, and the pump 10 are in operation. The siphon element 25 expanded 85 by the heat from the burner prevents flow of water through the drain pipe 23. Water from the feed water pump 6 is preheated in the coil 1 and mixes with water being delivered from the drum by the pump 10. 100

From the vaporizing coil the mixture of steam and water is delivered tangentially into the top of the drum 11 where the steam and water is separated. Steam from the top of the drum 11 is super-heated in the coil 3 and delivered to the engine 21. Exhaust steam is condensed by the condenser 22, the condensate being delivered to the hot well 7. When the burner 5 is shut down or for any other reason becomes inoperative, the sylphon element 25 contracts and opens the drain pipe 23, allowing all of the water in the inner compartment 15 of the drum to flow into the hot well 7. The water in the outer compartment 14, which constitutes a small portion of the total amount of water maintained in the drum, is retained. The check valve 19 in the outlet pipe 16 from the inner compartment prevents the flow of water from compartment 14 into the compartment 15.

When the steam generating system is again put into operation, the heat from the burner or steam from drum 11 through pipe 23 expands the sylphon 25, thereby closing the drain pipe 23. The pump 10 and the feed water pump 6 are put into operation. Water from the compartment 13, together with the additional feed water being added, is forced through the vaporizing coil 2. As only a small amount of water is retained by the compartment 14, it is soon heated up and a satisfactory steam pressure is obtained in a very short time. The device is provided with means, not shown, as it is not a part of this invention, for maintaining operation of the feed water pump until the level of water in the storage drum reaches a certain height. It is, therefore, evident that the water in the storage drum will gradually build up until it reaches the regulated height, due to the continued addition of water by the feed water pump 6, which is of a capacity sufficient to add more water to the system during constant operation than is removed in the form of steam.

It will be understood that the particular arrangement of compartments in the storage drum and the particular outlet means therefrom is only one modification of the invention. It is also to be understood that any suitable means operated by a condition of the boiler may be utilized to operate the bypass means for draining a major portion of water from the drum. Applicant limits his invention only by the scope of the appended claims.

What is claimed is:

1. In a steam generating system, water storage means, a vaporizing coil communicating with the storage means, means for circulating water from the storage means through the vaporizing coil, and means adapted to automatically remove the major portion of the water from said storage means at a predetermined temperature.

2. In a steam generating system, water storage means, a vaporizing coil communicating with the storage means, means for circulating water from the storage means through the vaporizing coil, means adapted to automatically remove the major portion of the water from the storage means at a predetermined temperature, and means for returning the water to the system during normal operation thereof.

3. In a steam generating system, a water storage drum, a vaporizing coil communicating with the storage drum, one end of said coil being connected to the bottom of said drum and the other to the top thereof, means for circulating water from the drum through the vaporizing coil, and means adapted to remove the major portion of said water from circulation at a predetermined temperature of a unit of the steam generating system.

4. In a steam generating system, a water storage drum containing a large and a small compartment communicating at the top of the drum, a vaporizing coil, means to deliver feed water to the inlet end of the vaporizing coil, means for connecting the outlet end of the vaporizing coil to the top of the storage drum, outlet pipes connecting each of the compartments to the inlet end of the vaporizing coil, check valves in said pipes, means for circulating water from the compartments through the vaporizing coil, and means to withdraw the water in the large compartment from circulation at a predetermined temperature of a unit of the generating system.

5. In a steam generating system, a cylindrical water storage drum, a cylindrical partition in said drum and spaced from the wall thereof forming thereby an annular outer compartment and a cylindrical inner compartment communicating at the top of the drum, a vaporizing coil, means for connecting one end of the vaporizing coil to the top of the storage drum and tangentially thereto, outlet pipes connecting each of the compartments to the other end of the vaporizing coil, check valves in said outlets, means for circulating water from the compartments through the vaporizing coil, and means for withdrawing the water in the inner compartment from circulation at a predetermined temperature of one of the units of the generating system.

6. In a steam generating system, a water storage drum containing a large and a small compartment communicating at the top, a vaporizing coil, a connection from the pre-heating coil to one end of the vaporizing coil, a water forcing means communicating with the same end of the vaporizing coil, means for connecting the vaporizing coil to the top of the storage drum, an outlet pipe connecting the large compartment to the water forcing means, a second outlet connection on a higher level than the first named outlet connecting

the small compartment to the water forcing means, check valves in the outlet pipe from the large compartment and the outlet from the small compartment, a drain pipe communicating with the bottom of the large compartment, and a heat controlled valve in said pipe adapted to drain the water from the large compartment at a predetermined temperature of one of the units of the generating system.

10 In testimony whereof I affix my signature.
CHARLES A. FRENCH.
